UNITED STATES PATENT OFFICE.

GEORGE H. BARTLETT, OF SAN FRANCISCO, CALIFORNIA.

INTERFOLDING-MACHINE.

1,347,242.

Specification of Letters Patent.

Patented July 20, 1920.

Application filed May 5, 1919. Serial No. 294,751.

To all whom it may concern:

Be it known that I, GEORGE H. BARTLETT, a citizen of the United States, residing at the city and county of San Francisco and State of California, have invented new and useful Improvements in Interfolding-Machines, of which the following is a specification.

This invention relates to an interfolding machine, and particularly pertains to a machine by which interfolded towels may be formed.

Due to the fact that interfolded paper towels have become quite generally used and that the machinery now employed in perforating and folding these towels is very expensive and cumbersome, it is the principal object of the present invention to provide a device by which rolls of towel blank may be fed through a machine and perforated at equal intervals therealong as fed and thereafter folded in interleaved relation to each other to be used in dispensing receptacles.

The present invention contemplates the use of a rigid main frame, within which are journaled a plurality of spindles, geared together so that they will rotate in synchronism and carrying suitable perforating and folding members between which the paper blank may be fed and be perforated and interfolded.

The invention is illustrated by way of example in the accompanying drawing, in which—

Figure 1 is a view in plan illustrating the completely assembled machine and clearly showing the arrangement of the perforating and folding element.

Fig. 2 is a view in perspective, disclosing a fragmentary portion of two towel blanks as they are perforated and in the position in which they will be folded.

Fig. 3 is a view in side elevation, showing the paper towels as interleaved.

Fig. 4 is an enlarged view, showing the co-operative relation of the perforating rolls to the folding element and the means for insuring a positive drive of the towel blanks therethrough.

Fig. 5 is an enlarged view in central section through the folding rolls, showing the manner in which they are formed to receive the towel-conveying members and the manner in which they co-operatively rotate.

Fig. 6 is a view in section and elevation, showing the perforating roll and the blades carried thereby.

Fig. 7 is a fragmentary view in section, disclosing the manner of operation of the perforating blade.

Fig. 8 is a view in perspective, disclosing one of the perforating blades.

Referring more particularly to the drawings, 10 and 11 disclose parallel and vertical frame members, which are rigidly connected by means of horizontal frame members 12 and 13. The member 13 is secured between the vertical members 10 and 11 at a point near the floor, while the member 12 is secured in a similar position, in superimposed relation to the part 13, and carries a number of reinforcing and bearing brackets, upon which the various rotating elements of the mechanism are supported. The rear vertical frame member 11 is provided with an extension bracket 14 which carries a pair of feed rollers 15 and 16. These feed rollers are positioned with their rotating axes in horizontal alignment and so disposed as to support the rollers 15 and 16 in a slightly spaced relation to each other. These rollers thus form an opening or throat through which paper blanks may be fed from a pair of magazine rolls 17 and 18.

The throat formed between the feed rolls 15 and 16 is substantially midway the height of the machine and lies in the operating plane thereof. Disposed at equal distances above and below the operating plane are perforating wheels 19 and 20. These wheels are mounted upon spindles 21 and 22 which are suitably journaled in the vertical frame member 11. Directly above the perforating roller 19 is a secondary perforating roller 24, while directly below the perforating roller 20 is a similar roller 25. These rollers co-operate with the complementary perforating rollers to form a series of perforations through the two parts of a paper blank and to extend substantially the full width of the paper, it being desirable in the present manufacture of paper toweling to leave a certain width of the toweling unperforated, so that the towel blanks will be one continuous piece as it is fed through the machine.

Mounted upon spindles 26 and 27, carried in journals upon the vertical frame member 10, and disposed in equal position upon opposite sides of the horizontal operating plane of the machine, are folding rollers 28 and 29. These rollers are formed with a plurality of blades extending longitudinally of their cylindrical faces. These blades or

teeth, as indicated at 30 on the two rolls, intermesh with each other to fold the two paper blanks in interleaved relation, as will presently be described.

- 5 The folding rollers 28 and 29 are adapted to be simultaneously driven by a suitable driving member and to rotate in unison with each other, due to the fact that their gears 31 and 32 are in constantly meshing position.
- 10 These gears are operated synchronously with gears 33 and 34 which are secured upon the spindles of the perforating rollers 19, 20, 24 and 25. By this means it is intended that all of the rollers, both perforating and folding, shall operate in synchronism, as the toweling is fed therethrough.

The toweling might be fed by conveyer elements 35 and 36. The elements 36 are led around the perforating rollers 19 and 20, while the elements 35 are led around the perforating rollers 24 and 25. As more particularly shown in Figs. 5 and 6, it will be seen that the perforating and folding rollers are both fitted with circumferential grooves into which the various roller elements 36 and 35 may feed. These elements are preferably in the form of coils or steel tapes and lead around the perforating rollers and the folding rollers.

- 30 Referring particularly to Fig. 1 of the drawing, it will be seen that the conveyer members 35 are led around the grooves in the folding rollers and then passed toward the passage formed in part by spring fingers of the machine to thereafter pass over idler pulleys 37 which are carried upon upper and lower brackets 38 formed as a part of the vertical frame member 11. From these pulleys the conveyers 35 are led around the pulleys 15 and 16 which form the throat 35 of the machine, after which the cables pass around the perforating rolls 19 and 20 and then return to the folding rolls. The conveyer elements 36 pass around the perforating rolls 19 and then around idler pulleys 39 which are carried in suitable bearings upon the frame portion 12.

In order that a predetermined tension may be exerted upon the conveyer members at all times, various pulleys 40 are disposed at convenient points upon the horizontal frame members and may be adjusted by means of a set-gage 41, acting in a slot 42. By operation of these pulleys the tension may be changed as desired and will thus insure that the paper blanks will be securely gripped as they pass between the various rolls of the machine.

- 60 Formed as a part of the vertical standard 10 is a horizontally extending supporting structure 44. This structure is formed with a horizontal passage 45, along which the folded and interleaved paper may pass from the folding rolls 28 and 29. This floor is also partially covered by means of yieldable

spring fingers 46 which will tend to hold the paper in its folded position and prevent it from becoming separated after having become interleaved. The yieldable fingers 46 are intended to partially obstruct the 70 movement of the folded blanks as they pass from the folding rolls. These fingers extend inwardly and along certain of the grooves 46', which are shown in Fig. 5 as being formed around the folding rollers and 75 which are intended to accommodate the conveying members 35 and the ends of the spring fingers 45 and 46. It is, of course, necessary that the spring fingers 45 and 46 extend in alternate grooves as considered 80 in relation to the conveyer belts 35. These fingers will thus strip the paper from the rolls and obstruct its movement in such a manner as to stack the paper and to hold it in its folded position. This makes it possible for the paper blank to be folded after 85 having been creased and thus will present them to an operator or to a suitable carriage by which they may be removed and packed in a condition for use in dispensing containers.

By reference to Figs. 7 and 8, it will be noted that the machine is provided with removable perforating blades 47 which have serrated faces 48 and are otherwise formed 95 with intermediate grooves 49; these grooves being designed to accommodate the conveying cables 35 and 36. In Fig. 7 it will be seen that the complementary blades of the perforating rolls 19 and 24 and 20 and 25 100 act in an overlapping manner to perforate the paper blank, as indicated by the member 50, thus forming a continuous line of perforations across the width of the toweling as interrupted by the space permitted by the 105 grooves 49.

In the operation of the present invention, blank rolls of paper toweling are placed upon the magazine cylinders 17 and 18 and thereafter led between the rollers 15 and 16 to pass to the perforating rolls 19 and 20. The path of travel of the paper is indicated in Fig. 4 where it will be seen that the paper blanks from the roll 18 will pass around the outer periphery of the roller 20 and between 115 the conveyer belts 35 and 36. By this means the conveyer belt 35 will hold the paper against the perforating rolls of the roll 20 and will combine with the belt 36 to form a channel-way within which the paper will be held as it is carried in the direction of the folding roll. At the same time the paper blanks from the roll 17 will be led upwardly and around the perforating roll 19, thereafter to pass between the conveying 120 belts 35 and 36 to the upper folding roll.

While the blanks are passing between the perforating rolls the blade 47 carried by these rolls will come into overlapping relation, as indicated in Fig. 7, and will act to 125 130

perforate the blank throughout its width. Due to the fact that the perforating rolls are in synchronism, blades will always bear the same relation to each other and the towel blanks will be perforated at equal predetermined intervals throughout their length. As the paper blanks pass from the perforating roll and to the folding roll they will be drawn between the folding rolls, and, as indicated in Fig. 4, will be folded between the various teeth of the rolls 28 and 29 during the course of their rotation. The position of the folding rolls, in relation to the perforating rolls, is such that the paper blanks will be folded along their perforations and midway therebetween and that the separate blanks, represented by the upper and lower rolls 17 and 18, will be perforated so that the perforations will be in folded relation to each other when the two blanks are interfolded.

By referring to Fig. 2, it will be seen that the perforations of the blanks of the rolls 17, as indicated at A, will be at the lower 25 crease of their folds, while the perforation of the blank from the roll 18, as indicated at B, will be in the upper crease of the fold, thus alternately disposing the perforations in relation to each other upon the separate 30 blanks and making it possible for one piece of towel to be drawn from the dispensing machine and automatically exposing the end of the next succeeding piece, although not completely withdrawing it from the container.

It will be evident that this machine may be used for clipping paper and interleaving paper of various widths without in the least modifying the spirit of the present invention 40 and that the device here shown will eliminate the use of objectionable and unreliable machines using a reciprocal movement and insuring that a continuous operation of perforating and interfolding will be produced 45 by rotary element.

While I have here shown the preferred form of my invention as now known to me, it will be understood that various changes in the combination, construction and arrangement of parts may be made by those skilled in the art without departing from the spirit of the invention as claimed.

Having thus described my invention, what I claim and desire to secure by Letters 55 Patent is—

1. In an interfolding machine, a pair of toothed folding rollers mating with each other, conveyer means for carrying flexible blanks to said rollers, and yieldable members 60 adapted to separate the blank from the rollers and to stack the paper folded thereby.

2. In an interfolding machine, a pair of rotary folding rolls, two pairs of perforating rolls, conveyer elements for each folding 65 roll engaged about the latter and about one

perforating roll of each pair of the latter and other conveyer elements engaged about the same perforating roll of each pair of the latter and coöperating with the first named conveyer elements.

3. In an interfolding machine, a pair of rotary folding rolls, two pairs of perforating rolls, conveyer elements for each folding roll engaged about the latter and about one perforating roll of each pair of the latter 70 and other conveyer elements engaged about the same perforating roll of each pair of the latter and coöperating with the first named conveyer elements, said other conveyer elements being disposed between the inner flights of the first named conveyer elements 75 and having inner terminals disposed adjacent the folding rolls.

4. In an interfolding machine, a pair of rotary folding rolls, an endless conveyer 80 member connected to each of the rolls, a pair of perforating rolls associated with each conveyer member and having the rolls arranged respectively on opposite sides of a flight of the member and a pair of endless 85 conveyers trained respectively around one of each of the rolls of the perforating rolls and coöperating with the respective first named conveyer members.

5. In an interfolding machine, a pair of 90 rotary folding rolls, two pairs of perforating rolls, and two pairs of endless conveyers, the two conveyers of each pair coöperating with each other and with the folding and perforating rolls.

6. In an interfolding machine, a pair of folding rolls, a pair of perforating rolls for each folding roll and a pair of endless conveyers for each folding roll and the pair of 95 perforating rolls thereof.

7. In an interfolding machine, a pair of folding rolls, a pair of inner spaced perforating rolls substantially alined therewith, an outer perforating roll coöperating with each inner perforating roll, and two pairs 100 of endless conveyers coöperating with the respective folding rolls and with the perforating rolls and with each other.

8. In an interfolding machine, a pair of folding rolls, a pair of inner spaced perforating rolls substantially alined therewith, an outer perforating roll coöperating with each inner perforating roll, an endless conveyer for each folding roll encircling the adjacent outer perforating roll, an endless conveyer encircling each inner perforating roll 115 and coöperating with the adjacent first named conveyer, the inner ends of the second conveyers terminating adjacent the folding rolls, and the first named conveyers having 120 parts spaced and substantially alined with the folding rolls.

9. In an interfolding machine, a pair of folding rolls, two pairs of perforating rolls spaced from the folding rolls, an outer end- 125

less conveyer engaged around each folding roll and coöperating with the rolls of the adjacent perforating rolls, and an inner endless conveyer coöperating with the first 5 named conveyer and with the respective other perforating rolls.

In testimony whereof I have hereunto set

my hand in the presence of two subscribing witnesses.

GEORGE H. BARTLETT.
